UNITED STATES PATENT OFFICE.

YENJIRO MORITA, OF ADZUMA-MACHI, NEAR TOKYO, JAPAN.

MECHANICAL PENCIL.

Application filed November 10, 1925. Serial No. 68,198.

This invention relates to a mechanical pencil or a sharp pencil, and more particularly to the inner tubular member and lead holding jaws containing a push rod.

5 An object of the invention is to provide a superior mechanical pencil which may be manufactured by a simple manner and with a minimum material and consequently at a lower cost.

10 In order that this invention may be clearly understood and readily carried into practice, reference may be had to the appended explanatory sheet of drawings in which:

15 Fig. 1 is a plan view showing three pairs of blanks for inner tubular members cut from a sheet metal,

20 Fig. 2 is a side view of the inner tubular member formed by joining together a pair of semi-tubular members cut from a sheet metal in the manner shown in Figure 1,

25 Fig. 3 is a longitudinal section of a completed mechanical pencil made according to this invention.

30 Referring to the drawings, the inner tubular member shown in Figure 2 consists of a larger sleeve portion 1, reduced central portion 2, and a further reduced portion or lead holding jaws 3, and is made of a pair of blanks cut out from a sheet metal as shown in Figure 1, each blank being bent to a semi-tubular shape so as to form a tubular member when joined together. The portions 1, 2 and 3 form an integral body.

35 In each blank there is provided a slot 4 in the central portion 2, and there is also provided another slot 5 in the larger portion. These slots 4 and 5 are preferably cut at the same time of cutting the blanks from a sheet metal by means of a punching press.

40 As shown in Figure 3, collars 6 and 7 are mounted on the both ends of the central portion 2, whereby the pair of the semi-tubular members is securely held. At the same time, a spiral wire 8 is mounted around the central portion 2, and surrounding the same is mounted a sleeve 9. Into the central portion 2 is inserted a push rod 11 hav-

ing a forked engaging member 10 which extends through the slot 4 and is engaged by the spiral wire 8, thus forming a lead propelling device. The extreme ends of the reduced portions 3 are slightly bent outwardly so that when they are introduced into the barrel 12, coming into contact with the inner surface of the conical part, they serve to hold the lead firmly. A lead magazine 13 is frictionally held inserted into the larger end of the inner tubular member, and onto the latter is mounted a head as in the usual manner. The parts are so assembled that the spiral wire 8 is held from turning with the inner tube 2 by the friction existing between the spiral wire 8 and the sleeve 9, and said sleeve is also held from turning by the friction existing between the same and the barrel 12.

45 As before mentioned, according to this invention the inner tubular member including spring jaws is formed by joining together a pair of semi-tubular members which are cut out from a sheet metal, and they are securely held by means of collars 6 and 7, without a necessity of soldering. So, according to this invention, improved 50 mechanical pencils may be manufactured with a lower cost, requiring a minimum amount of skill and labor.

What I claim is:

55 A mechanical pencil composed of a barrel, an inner tubular member having integral therewith lead holding jaws, said member comprising a pair of semitubular members, a collar on said inner tubular member and securing said semitubular members together, 60 a spiral wire surrounding the central portion of the inner tubular member and bearing against said collar, and a push rod having an engaging member extending through a slot formed in said central portion and 65 engaging the said spiral wire, and a sleeve in said barrel and surrounding said spiral wire and by friction preventing said spiral wire from turning with the inner tube.

70 In testimony whereof I affix my signature.
YENJIRO MORITA.
